Primary Examiner — Brian N. Vinson(74) *Attorney, Agent, or Firm* — Gottlieb, Rackman & Reisman, P.C.(57) **CLAIM**

The ornamental design for a connector for a lighting system, as shown and described.

DESCRIPTION

FIG. 1 is a perspective view of a connector for a light system showing my new design;

FIG. 2 is a first side elevational view thereof;

FIG. 3 is a second side elevational view thereof;

FIG. 4 is a third side elevational view thereof;

FIG. 5 is a fourth side elevational view thereof;

FIG. 6 is a top plan view thereof; and,

FIG. 7 is a bottom plan view thereof.

The broken lines shown in the drawings are included for the purpose of illustrating elements of the connector for a lighting system and form no part of the claimed design.
